UNITED STATES PATENT OFFICE.

CHARLES R. KITTLE, RESIDING NEAR INDO, CALIFORNIA, ASSIGNOR OF ONE-HALF
TO G. E. HARPHAM, OF LOS ANGELES, CALIFORNIA.

HYDROCARBON BURNER.

Application filed August 17, 1921. Serial No. 492,943.

To all whom it may concern:

Be it known that I, CHARLES R. KITTLE, a citizen of the United States, residing near Indio, in the county of Riverside, State of California, have invented new and useful Improvements in Hydrocarbon Burners, of which the following is a specification.

My invention relates to a burner designed to burn crude hydrocarbon oil associated with steam or compressed air and the object thereof is to produce a burner of varying capacity which is partly manually controlled and partly automatic in operation.

The burner illustrated in the drawings forming a part of this application is designed for use in a locomotive engine and will be so described although my burner can be used in the fire box of any steam boiler plant.

20 In the drawings Fig. 1 is a top plan of my burner, with parts in section and parts broken away. Fig. 2 is a front view of the burner head. Figs. 3-4-5 and 6 are views taken on the lines 3-4-5 and 6 of Fig. 2.

25 In the lower member 10 of the head is a vertical chamber 11 that is connected by pipe 12 to a source of crude oil supply, not shown. Resting upon member 10 is a partition which is composed of a bottom or port

30 plate 13 and resting upon the port plate is a chamber plate 14 which in the illustration shows three chambers, the one in the center being larger than the outside chambers. The center chamber 15 will be called, 35 the main chamber and the outside chambers 16 and 17 will be called the starting or pilot chambers. Plate 13 has one perforation or port 19 extending therethrough which opens into chamber 16, three ports 20 therethrough which open into chamber 15 and one port 21 therethrough which opens into chamber 17. On the top of plate 14 is the top member or cap 22. Extending through member 22 and through plates 13

40 and 14 and screwing into member 10 are the connection bolts 23 which unite the different parts of the head. There is some clearance around these bolts in member 22 as best shown in Fig. 3, and in plate 14. A 45 transverse channel 24 is bored from one side in cap 22 so as to connect the vertical holes 25. A transverse channel 26 is bored from the other side so as to open into vertical hole 27. A pipe 28 is connected into chan-

50 nel 24 and runs to and is connected into

channel 29 of the regulator head 30. Connected to head 30 is valve casing 31 which has a channel 32 therein in register with channel 29. Casing 31 has a valve chamber 33 therein in which is mounted poppet valve 34 which controls channel 32 as hereafter explained. Valve 34 has a stem 35 which extends into spring casing 36. In casing 36 is a coil spring 37 which bears against the end of stem 35. A tensioning screw 38 tensions the spring. Chamber 33 is connected by pipe 39 with channel 26. Head 30 has another channel 40 therein which crosses channel 29 at right angles. A stem 41 passes through channel 40 and carries a valve 42 on its inner end which controls channel 40. A steam supply pipe 43 connects channel 40 which is enlarged to receive the pipe and chamber valve 42 with the steam dome of the boiler not shown. Stem 41 has a head 44 which carries rollers 45 and 46 between which passes a curved control bar 47 one end of which is pivotally connected to member 48 of the control lever 49. The other end of bar 47 is adjustably connected to member 50 of lever 49. A slot 51 in member 50 provides for the adjustment of bar 47 at that end, thereby regulating the throw of the bar as hereafter explained. Lever 49 is adjustably mounted on rod 52 and is held in its adjusted position thereon by set screw 53. Rod 52 has rigidly mounted thereon an arm 54 which is connected by link 55 with arm 56 connected to the oil valve stopper 57 which is mounted in valve casing 58 on pipe 12.

Operation.

It will be understood that for ordinary running conditions spring 37 is tensioned to prevent valve 34 from operating and the engine is run by the fuel issuing from the pilot chambers. When climbing a hill or running faster than ordinary or when pulling a heavy load the steam is admitted into channel 29 to raise the pressure above the power of spring 37 and steam then passes through pipe 39 and out of chamber 15. At the same time and by the movement of lever 49 oil valve stopper is opened wider to admit more oil to chamber 11. A turn buckle 59 on link 55 can be used to regulate the oil valve stopper if desired.

By this construction it will be seen that under ordinary running conditions only the

pilot burners operate, but on extraordinary running conditions all the burners operate together. It will be further observed that the supply of steam and oil is increased or diminished by the operation of the single lever 49.

While I have described my burner as using crude oil and steam as the fuel it is obvious that compressed air or other elastic fluid could be used in place of steam. Any other hydrocarbon fuel can be used in place of oil. I have shown two pilot chambers, one at each side of the main chamber as I have found that such construction produces excellent results when the burner is used on a locomotive, but it is obvious that a single pilot burner could be used instead of two pilot burners. I have shown a regulatable poppet valve on the supply pipe leading to the main chamber as I prefer that construction but it is obvious that a manually operated valve could be used instead of the poppet valve.

Having described my invention I claim:

1. A hydrocarbon burner comprising a head having a plurality of independently operable chambers therein, one of said chambers being a main chamber; means to supply hydrocarbon liquid into said chambers; and means to supply an elastic fluid into said chambers; a poppet valve on the fluid supply of the main chamber intermediate said chamber and the supply means; and regulatable automatic control means for said poppet valve, whereby when the pressure in the supply means rises above a predetermined point said poppet valve opens and the main chamber is thrown into operation.

2. A hydrocarbon burner comprising a head having a plurality of independently operable chambers therein, one of said chambers being a main chamber; means to supply hydrocarbon liquid into said chambers; a regulating valve on said supply means;

means to supply an elastic fluid into said chambers, each chamber receiving its supply through a branch from the main supply means; a regulating valve on said elastic fluid supply means; a regulating valve on the branch which leads to the main chamber; an operating lever; and connections from the regulating valves on the supply means to said operating lever whereby the supply of hydrocarbon and elastic fluid can be increased or diminished by the movement of a single lever.

3. A hydrocarbon burner comprising a head having a main chamber and two pilot chambers; means to supply an elastic fluid into said chambers; a regulating valve on said supply means; a regulatable poppet valve on the supply means to the main chamber intermediate the regulating valve and the chamber; means to supply a hydrocarbon fluid into said chambers; a regulating valve on said fuel supply means; an operating lever; and a connection from the regulating valves to said lever, whereby the supply of elastic fluid and hydrocarbon fluid are increased or diminished by the movement of a single lever.

4. A hydrocarbon burner comprising a head having a plurality of independently operable chambers therein; one of said chambers being a main chamber; liquid supply means leading to said head and opening into each chamber; elastic fluid means leading to said head and then branching, a branch opening into each chamber; regulating valves on said main supply means; an operating lever connected to said valves; a valve on the branch to the main chamber; and means to control said last valve.

In witness that I claim the foregoing I have hereunto subscribed my name this 6th day of August, 1921.

CHARLES R. KITTLE.
